UNITED STATES PATENT OFFICE.

WILLIAM ALBERT BURNS, OF LONDON, ENGLAND, ASSIGNEE, BY MESNE ASSIGNMENTS, TO CHARLES GOLD, OF RAVENS, ENGLAND.

SIGN.

Application filed September 12, 1924, Serial No. 737,427, and in Great Britain September 20, 1923.

This invention relates to signs, particularly signs adapted to be placed upon the tops or roofs of buildings and in like elevated positions.

- 5 An underlying idea of the invention is to produce the illusion at night of illuminated lettering or devices apparently floating unsupported in space above the building or like, and the invention comprises the use of 10 transparent or translucent plane reflecting surfaces utilized for the above purpose substantially as hereinafter described. With such surfaces, a reflected image of a display device is adapted to be projected, and the 15 background to said translucent reflector is also visible therethrough, the image of said device thus appearing to float unsupported in said background which may be the sky.

Other parts of the invention comprise the 20 novel construction and arrangements embodied in the several preferred forms of the apparatus described and specifically claimed.

The invention is illustrated in the accompanying drawings in which—

- 25 Fig. 1 shows a simple arrangement of sign on the top of a flat-roofed building.

Fig. 2 shows a sign mounted on a roof sloping at 30 degrees.

- Fig. 3 shows a roof sign adapted to be 30 viewed by persons on the pavement of a neighbouring thoroughfare.

Fig. 4 is a modification of Fig. 3.

Fig. 5 shows a modification giving a remote image.

- 35 Fig. 6 illustrates a front view of a night sign.

Fig. 7 being a transverse sectional view.

Fig. 8 is a modification of Fig. 7.

Referring now to the drawings, 1 is the

- 40 front portion of the top of a flat-roofed building, 2 is the sign casing and the horizontal arrow 3 indicates the lettered portion of the sign. This is horizontal and may, together with its casing run any required 45 length along the top of the building. In practice, I prefer to employ white lettering on a black or nearly black ground, forming the white lettering of a translucent material capable of being illuminated at night by 50 lamps placed below it in the casing.

Above the casing is carried the translucent reflector 4, in this example, where the projection is intended to be horizontal, disposed at an angle of 45° to the horizontal

plane. This mirror may be of any suitable 55 material that does not unduly obstruct a direct view of the sky and/or other roofs or like features from the observer and may be, for example, of transparent glass or talc or celluloid or slightly tinted glass or the like, 60 and preferably runs the whole length of the lettered part of the sign. It may, however, be extended at either end for a short distance to increase the lateral field of view. This arrangement provides a sign no part of 65 which overhangs the street and which gives easy and safe access to any part of the casing to change the lettering or replace suspended lamps. The lettering may be sectional or individual for ease of change or 70 may be formed on a continuous band, or strip, capable of being moved along the length of the casing. Two or more rows of lettering may be carried on separate bands, each band being moved at a different speed 75 from its neighbour.

Figure 2 shows the casing mounted on the slope of a 30° roof. In this case, assuming the required projection to be horizontal, the mirror 4 is inclined to the horizontal at 30°. 80 This requires a relatively larger mirror than when the sign casing is horizontal and in practice we would prefer to raise the front of the casing on supports to bring it horizontal. In the arrangement shown both in 85 this figure and in Fig. 1, the apparent position 5 of the lettering is behind the mirror and the lettering will appear to float in space beyond the edge of the building. In all cases it is clear that the background to said transparent reflector will be visible therethrough 90 simultaneously with the image of said device.

In Fig. 3, 1 is as before the top of a flat-roofed building, 2 is the sign casing and 4 the mirror, here raised some height above the 95 sign casing. 7 is the roadway and 8 and 9 the pavements on either side of the roadway. In this example the sign is intended to be viewed by persons on the pavement 9 on the side of the roadway remote from the building carrying the sign. On a dark night the translucent reflector and its necessary supports, which would be painted black, would be substantially invisible to persons on pavement 9 but the reflected image 5 would be 100 clearly visible against the sky, the lettering apparently floating in the air without support. The higher the mirror 4 is carried 105

above the sign casing 3 the higher the apparent image of the lettering will be raised above the roof of the building.

Fig. 4 shows a similar arrangement but with the sign casing 2 inclined at 45° to the horizontal. In this case, assuming the required downward angle of the reflected rays to be also 45° the mirror 4 is horizontal. This gives a higher degree of reflection than that obtained by the arrangement shown in Fig. 3. It also permits of a second sign casing 2^a being placed under the mirror. The lettering of this second sign would not be visible to persons on pavement 9 with the mirror shown as in 4 but if the mirror is pivoted along its length so that it can be tilted into the position 4^a, the first sign 3 will disappear and the second sign 3^a take its place. Mechanical tilting of the mirror from one position to the other will cause the two signs to appear alternately. We may thus employ a tilting mirror to reflect two or more signs to the same line.

Fig. 5 shows an arrangement to enable a considerable apparent height of the image 5 to be obtained by a relatively low mirror 3. Here the lettering of the sign case 2, which is vertical, is reflected by an intermediate silvered mirror 6 on to the transparent mirror 4 and the apparent position of the image 5 is increased by the distance between the sign casing 2 and the intermediate mirror 6.

Referring now to Figs. 6, 7 and 8, the transparent mirror is represented at 10 and the arrangements are similar to those already described. The sign casing 11 has a series of lamps 12 disposed in a trough-shaped reflector 13 of parabolic section and is covered by a ground glass 14 and opaque black or colourless moving band 15 provided with transparent lettering or devices. The ground glass, or a stationary stencil, may be provided with a series of inclined parallel or 45 wavy lines or inclined surfaces sufficient to distort the view of the device transmitted therethrough so as to give a rather nebulous appearance to the image, confusing the eye as to distance and giving the illusion of a 50 moving luminous body of lettering floating at an indefinite distance. For this purpose fluted glass may be used. Alternatively a diffusing screen of ground or fluted glass or a coloured translucent screen may be disposed just above the band. The supports 16 for the back of the transparent mirror are masked by the front supports 17 which are formed and painted to resemble the silhouettes of chimneys or other suitable architectural features or the like according to the nature of the site. As shown in Figs. 6 and 7 the top supporting bar 18 is also masked by means of a vertical or inclined strip of unbordered glass or of silvered 65 mirror 19 reflecting another portion of the

sky blending into the background. The image in each case is represented at 20. The supports may be either at the ends of the mirror 10 or at intermediate points. As shown at Fig. 8 the transparent mirror 10 is supported wholly at its lower portion and the front structures 17 may be used only to mask the sides or dispensed with altogether. The casing 11 may be longer than the sign or shorter and particularly in the latter case the illumination may be caused to decrease gradually at the ends by means of suitably graded masks or shields, so that the moving lettering appears to fade away at each end of its zone of maximum brightness. A moving (preferably intermittent) cylinder or other illuminated device may of course be substituted for the band, and various modifications may be introduced in the details of the apparatus without departing from the invention; for example one direct and one reflected legend or device may be simultaneously reflected by the same transparent mirror, giving the effect of floating images in more than one plane.

In all cases the display device is arranged so as not to be directly visible along the line of sight of the observer of the image at substantial distances from the surface of the reflector. It is obvious that in the case of a 95 roof sign observed by passers-by in a thoroughfare the device will be invisible. In other cases any suitable mask may be employed to conceal it from direct view.

The invention is not confined to signs built 100 on the roof of a building, as the sign may be otherwise supported by means of any elevated support so as to produce the appearance of an image floating in the sky.

I claim:

1. A means for displaying a sign to be visible as floating in the air against the sky as a background, comprising a display device mounted by an elevation materially above the eye of the observer and wholly concealed by such elevation from the eye of the observer, a translucent reflector arranged above the display device and between it and the background, and at an angle other than a right angle to the display device to cause 110 the line of observation to be through the reflector to the background wholly beyond said elevation and said display device.

2. A roof sign wherein the display device is to be projected as visible as if floating in 120 the air with the sky as a background comprising a display device arranged on the roof in such a manner as to be wholly concealed by the roof structure from the eye of the observer below the roof, a translucent reflector 125 arranged at such a height above the roof and at such an angle to the display device that the line of vision from the eye of the observer through said reflector is wholly beyond the roof and permits a view of the sky back- 130

- ground in direct vision the reflector being arranged at such an angle to the display device as to project the characters from such device against that portion of the sky background as is in the line of observation. 5
3. A roof sign including a plurality of display devices, a translucent reflector through which the eye of the observer may view the sky as a background wholly beyond such display devices, and means for varying the angular relation of the translucent reflector to direct the projection from such display devices in the line of vision which is arranged wholly beyond the display devices and includes the reflector and sky background. 10
4. A means for displaying sign matter or the like as apparently floating under the open sky above a building, comprising a device located on and wholly concealed by an elevated portion of the building and adapted for displaying illuminating matter in an upward direction, a translucent reflector arranged at such a distance above the building and at such an angle to the display device as to reflect an image of the matter from said display device downwardly at a predetermined inclination to thereby determine the line of vision from an observer at the ground level to see the whole of such image apparently floating in the sky beyond the reflector and above the building. 15
5. A roof sign including a plurality of display devices seated upon the roof of a building and wholly concealed by said roof from
- the eye of the observer, a translucent reflector, a structure to raise said reflector in the line of vision of the observer and to interpose it between his eye and the normal background above the roof, and means to project the image from one of said display devices directly into the said line of vision and on to said reflector. 20
6. A roof sign including a plurality of display devices situated upon the roof, a translucent reflector arranged to reflect an image from one display device into the line of vision of the observer and a second reflector interposed optically between another display device and said translucent reflector so that the said translucent reflector also indirectly reflects an image from said other display device into the said line of vision. 25
7. A roof sign including a display device, a translucent reflector, a structure raising said reflector above the roof into the line of sight of an observer looking at the sky over said roof, and a second reflector interposed optically between said display device and said translucent reflector so as to present an image from said display device facing upwardly towards said translucent reflector, the arrangement being such that the apparent plane of the image reflected by the translucent reflector to the observer is thus further behind and above the translucent reflector than the distance between the two reflectors. 30
- In testimony whereof I affix my signature.
- WILLIAM ALBERT BURNS.
